UNITED STATES PATENT OFFICE

137,961

DESIGN FOR A COMBINED CASSEROLE AND SERVING PLATTER

Thomas Kapner, Bellaire, Ohio, and David Kamenstein, New York, N. Y.

Application March 10, 1944, Serial No. 112,850

Term of patent 3½ years

(Cl. D44—15)

To all whom it may concern:

Be it known that we, Thomas Kapner and David Kamenstein, citizens of the United States, residing in Bellaire, Belmont County, State of Ohio, and the Borough of Manhattan, city, county, and State of New York, respectively, have invented a new, original, and ornamental Design for a Combined Casserole and Serving Platter, of which the following is a specification, reference being had to the accompanying drawing, forming a part thereof, in which:

Fig. 1 is a top plan view of a combined casserole and serving platter embodying our new design;

Fig. 2 is a side elevational view thereof;

Fig. 3 is a top plan view of the casserole with the cover removed; and

Fig. 4 is a plan view of the cover reversed from the position shown in Fig. 1, such cover serving as a platter for the food in the casserole.

We claim:

The ornamental design for a combined casserole and serving platter, as shown and described.

THOMAS KAPNER.
DAVID KAMENSTEIN.
